CHEMICAL PROCESS

Edward D. Reeves, Cranford, and Stewart H. Hulse, Westfield, N. J., assignors to Standard Oil Development Company, a corporation of Delaware

Application August 31 1939, Serial No. 292,780

2 Claims. (Cl. 196—55)

This invention relates to the treatment of hydrocarbon oils and refers more particularly to the thermal treatment of hydrocarbons in the presence of a solid substance which adsorbs carbonaceous material formed during the said treatment and also exerts an abrasive action on the walls of tubes and vessels with which the oil comes into contact thus tending to prevent accumulation of tarry deposits thereon.

It is a matter of record to treat hydrocarbons in the presence of activated carbon for the purpose of catalyzing the cracking of hydrocarbons. Activated carbon has been found to be a fairly active catalyst for various thermal reactions, say where relatively heavy hydrocarbons are converted to hydrocarbons boiling within the gasoline range.

In the treatment of heavy petroleum materials such as reduced crude containing large quantities of low gravity tar and the like, it is extremely difficult to convert such feed stocks to valuable products in the gasoline, kerosene and heating oil range without suffering large losses due to gas and coke formation. In addition, thermal treatment of such stocks results in heavy coke deposits in the heating coils and soaking drums or stills requiring frequent shutdowns and sometimes impairing the equipment.

An object of the present invention resides in the use of the coke produced during the conversion of relatively heavy stocks, such as reduced crude, heavy gas oil or the like to form products of lower viscosity and boiling range.

Another object of the present invention involves the use of the coke formed during the thermal treatment of hydrocarbons in the preliminary treatment of reduced crudes and heavy gas oils prior to a final catalytic treatment employing other adsorbents, such as acid-treated clays, zeolites, synthetic silica-alumina gels, and the like.

According to the present invention, preferably the coke which is employed in the thermal treatment of hydrocarbons is that formed in a treatment of petroleum, e. g. a cracking operation. This coke is preferably ground to a powder of a size such that substantially all of it will pass through screens of from 100 to 400 mesh. This powder is preferably injected into a petroleum stock, such as reduced crude or a heavy gas oil in the form of a suspension. That is to say, it may be first dispersed into a gas, such as steam, nitrogen, hydrogen, or flue gas or mixtures of two or more of these gases and then injected into the oil to be treated.

In copending application Serial No. 267,993, filed April 4, 1939, there is described and claimed the use of pumice or clay for a similar purpose, but there the adsorbent required regeneration for further use.

In order to give a more detailed explanation of my present invention, reference is now made to the accompanying drawing which shows diagrammatically and in partial vertical section a suitable apparatus in which the present invention may be performed.

And to give a concrete example of this invention, the processing of a heavy gas oil having an A. P. I. specific gravity of 15 and a boiling range of from 450° to 1400° F. will now be described with reference to the drawing. The gas oil may be introduced into the system through line 1 and then passed through a furnace 2 where the feed stock is heated to a temperature of about 900° F., the heated stock being then withdrawn through line 3. Simultaneously, a dispersion of powdered coke produced in a previous treatment, which coke was dispersed in steam in dispersion chamber 4, in a manner hereafter more fully described, was injected into the heated oil stream through line 5. The heated gas oil containing the powdered coke was then passed through a coil 7 in a furnace 6 where the temperature was increased to about 1000° F. The pressure maintained on the oil in the coil 7 in the furnace 6 was about 100 pounds gauge and the time required for the oil to pass through the coil was about 10 seconds. The ratio of added coke to oil was about 1 part by weight of coke to 1 part of oil on a cold oil basis. The oil was withdrawn from the coil 7 through line 8 and passed to a cyclone separator 9 where the coke was removed from the vapors and passed downwardly over the inclined baffles 11 in vessel 10. Meanwhile, in order to assist the removal of the vapors from the coke, steam at a temperature of about 1000° F. was introduced into the bottom of vessel 10 through line 31. The mixture of oil vapors and steam was withdrawn through line 12, passed through a cooler 14 which condensed the water, then passed through line 15 to a separator 16 where the water separated in a lower liquid layer. The cracked products were withdrawn through line 17 to a fractionating tower 18 or they might have been passed directly to line 19 and thence to condenser 20 and finally to an accumulator 21.

In the process just described the operating conditions will of course vary according to numerous factors including the character of the

feed stock, the type of product desired and other variables. As a matter of fact in the process described the main product would be a crackable stock, i. e. a stock better adapted than the original stock for cracking to form gasoline in a thermal operation or preferably in a catalytic cracking operation employing an activated clay catalyst or the like. In producing the above cracking stock, the yield from 1000 lbs. of original material would be, under the conditions referred to, about 950 lbs. of a gas oil boiling within the range of about 400 to 850° F. with about 45 lbs. of coke and about 5 lbs. of gas.

In general, it may be stated with further reference to operating conditions that temperatures of from 750° to 1100° F. may be employed in the coil 7, that the time the oil is resident in the coil may be from 5 seconds to 50 seconds, that pressures of zero pounds per square inch gauge to 150 lbs. per square inch gauge may prevail in the coil 7 and the ratio of adsorbent coke to oil in coil 7 on a weight basis and calculated with reference to a unit of cold oil is from about .2 to 20 parts of catalyst to 1 part of cold oil. Since high temperatures may be employed without excessive coke deposition, the product distribution is favorable and conversions per pass are relatively high from high boiling feed stocks. Of course with lower boiling feed stocks operating conditions will be less severe as to temperature and time of reaction.

Referring now to the coke which had been removed from the oil vapors in baffled tower 10, the same may be conveyed, in a manner herein-after more fully explained, by star feeder 30 into a grinding chamber 32 having grinding rolls 33 and from there discharged through line 34 into hopper 35. Hopper 35 is provided at near its base with a compression screw 36 which is in communication with steam chest or dispersing chamber 4. Steam from some source is led into the system through line 22, passed through superheater 23 and thence through line 24 into the chest 4 at a point substantially opposite the discharge end of screw conveyer 36 within the chest. The temperature of this steam is about 1000° to 1100° F. and it impinges against the falling coke discharged through screw 36. The amount of steam gravimetrically should be about 2 or 3% of the amount of coke. The linear velocity of the steam is sufficient to form a moving entrainment or dispersion of coke in steam. The dispersion of coke is then discharged into line 5 and as previously mentioned, is then discharged into line 3. The pressure on the steam in chest 4 is of course greater than that on oil in line 3. Good results are obtained by providing a steam pressure in chest 4 of from 5 to 10 lbs. gauge greater than in oil line 3.

Referring back to the coke in vessel 10, the same is deflected, in whole or in part, by a swinging damper 37, pivoted at 40 and adapted to be swung about the pivot by a handwheel or the like (not shown) operable outside the pipe

5 into a discharge line 42. The coke will have increased in size by accretion during the passage of the fine powder, introduced through line 5 into the oil stream, through the treating zone. For most commercial purposes, the coke which is withdrawn from the system through line 42 should be in lump form.

On the other hand, if it is desired to obtain a finely divided coke, damper 37 is set at a vertical position thus permitting all of the coke to be discharged into grinding chamber 32. Coke not to be recycled which is discharged into hopper 35 from chamber 32 is deflected by a rotatable damper 37-A toward conveyer 38 and thus withdrawn from the system. Of course, by obvious manipulation of dampers 37 and 37-A both coarse and fine coke may be withdrawn from the system. As heretofore stated, the coke to be recirculated should be in the form of a powder.

It will be understood that the mechanical specific means shown and described to carry out the present invention do not constitute a limitation on the invention since obviously other apparatus could be employed to accomplish the same or equivalent results. For example, by employing a compression screw of good efficiency it would be possible to discharge the recirculated coke directly into a shell type reactor thus eliminating the steam chest 4. Also means are available for separating the coke from the vapors other than the cyclone separator 9 shown. For instance, fine mesh screens as well as electrical precipitators may be used. It may be necessary in some processes to employ a second cyclone precipitator or a primary cyclone separator and an electrical precipitator to remove all the coke from the hydrocarbon vapors prior to condensation or fractionation.

Numerous modifications of the present invention falling within the spirit of the present invention will occur to those skilled in this art and the invention is to be construed as broadly as the terms of the below claims will permit.

We claim:

1. The method of reducing the viscosity of a relatively heavy hydrocarbon oil boiling within the range of from about 450° F. to about 1400° F. which comprises preheating said hydrocarbon oil, forming a dispersion of petroleum coke in an inert gas, injecting the dispersion of coke into a confined stream of said oil, further heating said oil containing the added coke in a reaction zone to a temperature within the range of from about 750 to about 1400° F. for a period of about 10 seconds, removing the coke from the reaction product and recovering said product.

2. The process as set forth in claim 1 in which a pressure of about 100 lbs. per square inch gauge is maintained on the oil in the reaction zone.

EDWARD D. REEVES.
